US00D399499S

United States Patent [19]

Kaneko et al.

[11] **Patent Number:** **Des. 399,499**[45] **Date of Patent:** **Oct. 13, 1998[54] **POINTING DEVICE**

- [75] Inventors: **Steven T. Kaneko; Aditha May Adams; Christopher Alviar**, all of Seattle; **Ferdinand van Engelen**, Bellevue; **Dana Kim**, Redmond; **Bridget Cameron Greenberg; Dick C. K. Liu**, both of Bellevue, all of Wash.
- [73] Assignee: **Microsoft Corporation**, Redmond, Wash.

[*] Notice: The term of this patent shall not extend beyond the expiration date of Pat. No. Des. 382,261.

[**] Term: **14 Years**

[21] Appl. No.: **50,267**

[22] Filed: **Feb. 13, 1996**

CLAIM

The ornamental design for a pointing device, as shown and described.

DESCRIPTION

FIG. 1 is a front isometric view of a pointing device showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
